(57) **CLAIM**

The ornamental design for a snow shovel replacement blade, as shown and described.

DESCRIPTION

FIG. 1 is a front elevational view of the snow shovel replacement blade of the present invention;

FIG. 2 is a rear elevational view of the snow shovel replacement blade of FIG. 1;

FIG. 3 is a left side elevational view of the snow shovel replacement blade of FIG. 1, the right view being a mirror image thereof;

FIG. 4 is a top plan view of the snow shovel replacement blade of FIG. 1, the bottom view being a mirror image thereof;

FIG. 5 is an enlarged, environmental left side elevational view thereof; and,

FIG. 6 is a reduced scale, environmental, bottom, front, right side perspective view thereof.

The broken lines showing of a shovel in FIG. 6 and a shovel blade and rivet in FIG. 5 are for illustrative purposes only and form no part of the claimed design.
